CLAIM

The ornamental design for a case for electronic communications device, as shown and described.

DESCRIPTION

FIG. 1 is a front perspective view of a case for electronic communications showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing the inner shell component of the case in isolation for clarity of disclosure;

FIG. 10 is a rear perspective view showing the inner shell component of the case in isolation for clarity of disclosure;

FIG. 11 is a front perspective view showing the outer frame component of the case in isolation for clarity of disclosure;

FIG. 12 is a rear perspective view showing the outer frame component of the case for clarity of disclosure;

FIG. 13 is an exploded front perspective view showing the components of the case separated for clarity of disclosure; and,

FIG. 14 is an exploded rear perspective view showing the components of the case separated for clarity of disclosure. The broken lines throughout the drawing figures depict portions of the case for electronic communications device that form no part of the claimed design. The broken lines and regions bounded by broken lines form no part of the claimed design.
